CLAIM

The ornamental design for a vacuum cleaner base, as shown and described.

DESCRIPTION

FIG. 1 is a front, right perspective view of a vacuum cleaner base showing our new design;

FIG. 2 is a top view thereof;

FIG. 3 is a left side view thereof;

FIG. 4 is a right side view thereof;

FIG. 5 is a front view thereof; and,

FIG. 6 is a rear view thereof.

The details shown in broken lines form no part of the claimed design.
